US00D995540S

(12) **United States Design Patent** (10) **Patent No.:** **US D995,540 S**
Alhimiri (45) **Date of Patent:** **** Aug. 15, 2023**

(54) **DISPLAY SCREEN OR PORTION THEREOF WITH A MEDICAL CHARTING USER INTERFACE**

(71) Applicant: **Saleise Health LLC**, Bloomfield Hills, MI (US)

(72) Inventor: **Ali Alhimiri**, Bloomfield Hills, MI (US)

(73) Assignee: **SALEISE HEALTH LLC**, Bloomfield Hills, MI (US)

(**) Term: **15 Years**

(21) Appl. No.: **29/775,355**

(22) Filed: **Mar. 23, 2021**

CLAIM

The ornamental design for a display screen or portion thereof with a medical charting user interface, as shown and described.

DESCRIPTION

The FIGURE is a front view of a display screen or portion thereof with a medical charting user interface.

The outermost broken lines illustrate a display screen or portion thereof and form no part of the claimed design. The remaining broken lines illustrate portions of the user interface that form no part of the claimed design.
